UNITED STATES PATENT OFFICE.

IVERN W. GROTHEY, OF YORK, PENNSYLVANIA, ASSIGNOR TO SCOTT & WILLIAMS
INCORPORATED, OF CAMDEN, NEW JERSEY, A CORPORATION OF NEW JERSEY.

AUTOMATIC STOP MECHANISM FOR KNITTING-MACHINES.

1,189,684.

Specification of Letters Patent.

Patented July 4, 1916.

Application filed March 2, 1912. Serial No. 681,064.

To all whom it may concern:

Be it known that I, IVERN W. GROTHEY, a citizen of the United States, residing at York, in the county of York and State of Pennsylvania, have invented certain new and useful Improvements in Automatic Stop Mechanism for Knitting-Machines, of which the following is a specification, reference being had to the accompanying drawings.

This invention comprehends certain new and useful improvements in knitting machines, and relates particularly to mechanism for automatically stopping the machine by tripping the belt shifter and by automatically applying a brake, in case the yarn or thread becomes knotted or breaks or is of too great a tension.

The invention has for one of its primary objects, a simple and efficient construction of stop mechanism of the nature just specified, which will act automatically to instantly stop the knitting machine should a knot be formed in the yarn or thread or 25 the tension increased, and which will embody one or more tension fingers that will normally hold the thread or yarn under the required tension as it is fed from the spools to the head of the knitting machine, 30 the parts being so constructed and arranged that immediately upon an obstruction or knot in the yarn engaging a knot-catcher embodied in the mechanism, the tension finger will move in a direction to trip the 35 device and stop the machine, the movement of the tension finger being in a rearward direction or in the direction of the source of the yarn supply and of such character, as will be hereinafter and more fully 40 described, as to at once strip itself of the yarn without substantially changing the position of the entering run of yarn.

The invention also has for its object a stop mechanism of this character, the parts 45 of which are so constructed and arranged that the same tripping mechanism may be used with more than one thread, the tensioning and throw-off fingers, for the separate threads or yarn, being both connected 50 to the same tripping mechanism, but each operable without affecting the other, whereby should one thread or yarn become too taut or broken, the machine will be stopped

and the knotted yarn immediately thrown off, without affecting in any way the other 55 thread or yarn.

A further object of the invention is a machine of this type which will embody a setter shaft capable of operating with two threads or yarns and carrying, independently movable feeler fingers, either one of which may be actuated independently of the other to trip the mechanism by disengaging the setter shaft from its co-acting latch, 60 in case the thread or yarn breaks.

A still further object of the invention is a stop mechanism for the purpose described which will include a novel and extremely simple and useful form of trip device for tripping the belt shifter and applying the 70 brake, and which will also embody a novel and extremely simple and efficient means for manually setting the apparatus.

The invention also has for its object in a mechanism of this character, an improved 75 construction and arrangement of stop device for the thread or yarn, provided with a plurality of slotted guide fingers, the slots of which are of varying widths, according to the diameter of the thread or yarn to be, 80 passed into the knitting machine, said stop devices being capable of revoluble adjustment so that they may be held in the required position to present the required finger in the path of movement of the yarn 85 or thread between the lower and upper relatively stationary guides. And the invention also aims to generally improve this class of devices and to render them more useful and commercially desirable. 90

With these and other objects in view, as will more fully appear as the description proceeds, the invention consists in certain construction, arrangements and combinations of the parts that I shall hereinafter 95 fully describe and claim.

For a full understanding of the invention, reference is to be had to the following description and accompanying drawings 100 in which,

Figure 1 is a rear elevation of an automatic stop mechanism embodying the improvements and principles of my invention. Fig. 2 is an enlarged face view of a portion of the apparatus with the cover plate 105 of the casing removed. Fig. 3 is a detail

sectional view on the line 3—3, of Fig. 9. Fig. 4 is a side elevation of the apparatus. Fig. 5 is a transverse sectional view on the line 5—5, of Fig. 1. Fig. 6 is a detail view 5 of the base of the apparatus partly in section on line 6—6, of Fig. 4, and with parts broken away. Fig. 7 is a detail perspective view of one of the knot catchers and the means for holding the same under tension 10 in adjusted position. Fig. 8 is a detail perspective view of the upper end or head bracket of the machine. Fig. 9 is an enlarged sectional view through the devices for tripping the belt shifter and for applying the brake. Fig. 10 is a detail perspective view of the setter shaft, and, Fig. 11 is a transverse sectional view, the section being taken approximately on the line 11—11, of Fig. 2, and showing a thread 15 or yarn passing through one of the feeler fingers and its co-acting frame.

Corresponding and like parts are referred to in the following description and indicated in all of the views of the accompanying 20 drawings by like reference characters.

My improved automatic stop mechanism for knitting machines embodies a base 1 which is formed with socketed arms 2 in which spool-holding rods 3 are detachably 25 connected as by set screws 4. The base 1 is also formed at right angles to the arms 2, with upwardly facing socket members 5 which are designed to receive the lower ends of vertically and upwardly extending posts 30 or uprights 6, the same being secured in the socket members 5 in any desired way, as by set screws 7. These posts or upright rods 6 extend parallel to each other, as clearly illustrated in Fig. 4, one in advance of the 35 other in relation to the head 8 of the knitting machine.

The thread or yarn 9 is adapted to pass from the spools 10 upwardly through lower guides 11 which, in the present embodiment 40 of the invention, are formed as eyes in the ends of a transversely extending wire rod 12 which is secured to the foremost upright or post 6 by a set collar 13. The yarn also passes upwardly through corresponding 45 guides 11^a and thence upwardly and forwardly and is looped once around the downwardly and forwardly projecting extremities 14 of tensioning detector and throwoff fingers 15 that are pivotally mounted upon 50 studs 16 projecting laterally from the relatively free end of a horizontally disposed and forwardly projecting bracket 17 secured upon the upper ends of the uprights 6. From the extremities 14 of the fingers 15, which 55 lie substantially in the axis of rotation of the knitting head, the yarn or threads 9 pass downwardly to the head 8, it being particularly noted that immediately upon being looped around the extremities 14 of the 60 fingers 15, the threads or the like extend

downwardly into engagement with relatively stationary bowed arms 18 constituting open U-shaped loops that are formed by downwardly, outwardly and rearwardly extending wires secured to the relatively free 70 end of the horizontal bracket 17. This construction of the tension fingers 15, in which the fingers are substantially vertical, and in which their movement to drop the yarn takes place in a plane radially of the vertical center of the machine, and directly toward the fixed yarn guides, and the yarn supply at the rear of the machine, is very advantageous, since it enables the loop of too 75 tense yarn to be dropped with a minimum motion of the tension detector element. It will also be obvious that the loop is dropped, by this arrangement, so that the continued running of the yarn for the short interval preceding complete stoppage carries the 80 dropped yarn well clear of the other normal yarn, and in a path leading from the guide 85 11^a in an advantageous position for quickly finding and removing the knot or slug which caused the stoppage, and rethreading the 90 machine.

As best illustrated in Fig. 8, the fingers 15 are coiled around the stud 16 to form their pivot bearings, and are thence extended upwardly, as indicated at 19, and connected, respectively, to rearwardly extending rods 20 which extend parallel to each other in laterally spaced relation and which freely pass rearwardly through separate and distinct apertures formed in a laterally elongated lip 21 which is formed on the periphery of a disk 22 mounted to turn about a central axis 23 in the form of a stud projecting from the bracket 17. The rear extremities of these rods 20 are hooked or turned 105 angularly, as indicated at 24, whereby either one of the rods may be pulled forwardly and thereby turn the disk 22 without moving or otherwise affecting the other rod 20. The rods 20, and consequently the fingers 15 that 110 are pivotally connected thereto, are held under tension by means of springs 25 which are coiled around tensioning screws 26 journaled in the bracket 17 and are connected at one end thereto, the other ends of said 115 springs extending upwardly through loops or eyes 27 formed in the rods 20, whereby by tightening up the screws 26, the tension of the springs may be increased, and by loosening these screws, the tension of the springs 120 25 may be decreased, as required.

To the disk 22, a vertically extending elongated rod 28 is eccentrically and pivotally connected at its upper end. This link rod extends downwardly from the disk 22 and at 125 its lower end passes loosely through a hole in and is hooked beneath a crank arm 29 which extends rearwardly from a transversely extending shaft 30 journaled in a casing 31 supported by the rearmost upright 130

6, said shaft 30 being mounted for partial rotation or oscillation about its longitudinal axis. The shaft 30 extends entirely across the casing and is provided midway of its ends and preferably as an integral part of the crank arm 29, with a lug 32 which projects downwardly from the shaft and which is designed for engagement with a shoulder 33 formed on a spring catch 34 pivotally mounted at 35 in the casing 31. The spring catch 34 is held under tension by a spring 36, the spring being connected at one end to the casing wall and at its upper end to the catch and extending across the pivot point 10 or center of movement of the catch, whereby the spring will have an increasing tension as soon as it has passed the center during its operation of moving the catch, and will thus quickly snap the same forwardly 15 in its operative movement. A light spring 37 is coiled around the shaft 30 and exerts a tension thereon in a direction to move the lug 32 into engagement with the shoulder 33, whereby when the catch is moved over to the position illustrated in Fig. 2, by means 20 that will be hereinafter fully described, the shaft 30 will automatically set itself and hold the catch under tension by the engagement of the lug 32 with the shoulder 33.

25 The shaft 30 is provided at each end with an angular pin 38 constituting a crank arm which is designed for engagement by the supporting bar 39 which is mounted upon the adjoining reduced journal end 40 of the shaft and which carries at its free end, the feeler fingers 41 that are designed, in their normal positions, to be located between frame rods 42, with the yarn or thread passed in and out between said fingers and rods. The fingers 41 have a tendency to move out from the frame rods 42 due to the vertically off-set position of their pivots 40 and will drop in case the thread or yarn breaks, in which event, the bars 39 will 40 move around and strike the angular pins 38 so as to disengage the lug 32 from the catch 34 and permit the latter to act under the influence of its spring 36.

45 A lower tension member or link rod 43 is pivotally connected at its upper end to the catch 34 and passes downwardly out of an opening 44 formed in the casing 31, said link rod being connected at its lower end to a latch 45 which is pivoted at 46 on a post 47 rising from the base 1. The latch 45 is formed with a shoulder 48 and with a setting cam 49 designed for engagement by a setting arm 50 which is secured to a shaft 51 supported by the base 1, said shaft being 55 provided with an actuating handle 52. At this point, it will be understood that when the handle 52 is moved in one direction, the arm 50 will engage the cam 49 of the latch 45 and swing the latch 45 in a direction to 60 pull down upon the link rod 43 so as to

effect the interlocking engagement of the catch 34 and shaft 30. This is the normal inoperative position of the parts.

Secured to the opposite side of the casing 31 are adjusting screws 53 which are held 70 under tension by springs 54 and which support axially movable knot catchers 55, each of which is formed with a plurality of fingers 56 formed with slots 57 of varying widths, whereby any of said fingers may 75 be brought into proper position to have the thread or yarn passed through it and to engage a knot or other obstruction on the yarn. In order to hold these stop devices in place after they have been axially adjusted, each tensioning screw 53 is provided with an inwardly projecting pin 58, and the fingers 56 are formed with sockets or recesses 59 for the reception of said pin. By drawing either of the devices inwardly, 80 the pin 58 will be disengaged from one of the recesses 59 and the stop device may be turned for adjustment and again locked in adjusted position.

The shaft 51 is encircled by a spring 60 90 which is designed to turn it, the shaft being held under tension against such turning movement by the engagement of its arm 50 with the shoulder 48 of the latch 45. The said shaft carries a trip arm 61 which 95 is designed to engage the angular end 62 of a shaft 63. This shaft is journaled on the head of the knitting machine and carries a crank arm 64 which is designed to engage an operating handle 65 on a shaft 66. This 100 last named shaft has a crank connection 67 with a link 68 pivotally connected to the belt shifting rod 69 constituting a toggle joint, whereby when the shaft 66 is turned in a direction to break the joint between the 105 crank 67 and link 68, the springs 70 of the belt shifting device will be permitted to act and thereupon immediately shift the belt from the fast pulley to the loose pulley so as to deprive the knitting machine of power. 110 At the same time, the movement of the shaft 63 which has, through the instrumentality of the cranks 64 and 65, turned the shaft 66 and tripped the belt shifting device, will by means of its upwardly extending arm 71, 115 move the lever 72 laterally away from the upwardly facing shoulder 73 upon which it rests, against the tension of the spring 74 surrounding its pivot 80, which is free for slight lateral movement in a flared bore 81 in the machine frame (see Fig. 3), and the brake actuating spring 75 connected to said lever, will then be permitted to act to carry the brake shoe 76 down into engagement with the brake disk 78 which is secured on 120 the drive shaft 77 of the knitting machine, thereby bringing such shaft quickly to a standstill.

From the foregoing description in connection with the accompanying drawings, 125

the operation of my improved automatic stop mechanism for knitting machines, will be apparent. In the practical use of the device, the yarn, for instance, is threaded 5 up from the spools 10 through the lower guides 11, through the slots 57 of corresponding knot-catchers 56, between fingers 41 and 42 through the upper guides 11^a and thence looped around the forwardly and 10 downwardly projecting extremities 14 of the tension detector fingers 15, and thence to the needles that are carried by the head 8 (not shown). The handle 52 is actuated in a direction to draw downwardly upon the 15 latch 45 and is engaged with the shoulder 48 thereof, and the brake actuating lever 72 is raised by this handle 78 and engaged with the shoulder 73 so as to hold said lever in an inoperative position against the tension 20 of its spring 75. The downward movement of the latch 45 and its consequent downward pull upon the link rod 43 will, as is evident, have caused the catch 34 to be moved to the left, as viewed in Fig. 2, whereupon the 25 spring 37 will cause the shaft 30 to turn in a direction to effect the interlocking engagement of the lug 32 and shoulder 33, and the parts will then be all in set position, ready for operation, should the yarn become knot- 30 ted or broken, or the tension of the yarn increase unduly. It will, of course, be understood that the yarn is passed in and out between the fingers 41 and the frame rods 42, the feeler fingers being thereby held in a 35 relatively upright position.

Should the yarn become knotted, it is evident that when the knot arrives at the knot catcher finger 56, through the slot of 40 which the yarn is passing, the movement of the yarn will be arrested at that point and consequently the downward pull upon that portion of the yarn which is passing to the head 8 of the knitting machine, will cause the tensioning finger 15 of such yarn to 45 swing rearwardly about its stud axis 16, the yarn, by this rearward movement of the finger automatically stripping itself therefrom, while at the same time, a forward pull will be imparted to one of the rods 20, 50 the disk 22 will consequently be turned and the link rod 28 will be pulled upwardly so as to release the lug 32 from the shoulder 33 of the catch 34, and the spring 36 of said catch will immediately act to snap the latch 55 over to the right, as viewed in Fig. 2, and pull upwardly upon the lower link rod 43, thereby disengaging the shoulder 48 of the latch 45 from the arm 50 and permitting the shaft 51 to be turned by its spring 60 in 60 a direction to trip the shifting device and to automatically apply the brake. Thus the machine will be at once brought to a standstill. The same action will take place should the yarn break, for in that event, one 65 of the feeler fingers will drop forwardly

and its bar 39 will strike one of pins 38 so as to disengage in that manner the lug 32 from the shoulder 33 of the catch 34.

While the accompanying drawings illustrate what I believe to be the preferred embodiment of my invention, it is to be understood that the invention is not limited thereto, but that various changes may be made in the construction, arrangement and proportions of the parts without departing 75 from the scope of the invention, as defined in the appended claims.

What I claim is:—

1. In a yarn actuated stop mechanism the combination of supporting guides through 80 which the yarn is adapted to be passed, a support for said guides, a tension detector pivoted on said support and depending from said pivot, said detector having a downwardly projecting bent extremity over which the yarn is adapted to be passed, whereby movement of the detector through a short arc wholly beneath said pivot will cast off the yarn at or near the completion of a movement ending substantially at the vertical, in combination with power-release devices and actuating connections between said detector and power-releasing devices. 85

2. In a stop mechanism for a knitting machine, a tension detector over which the 90 yarn is adapted to be passed to the knitting machine, a support to which said detector is pivotally connected, said detector having freedom of movement toward the axis of the machine, means for actuating the stop 95 mechanism, and a substantially vertical and upwardly open fixed guide for the yarn substantially on the vertical axis of and above said machine, the detector being adapted to move through the opening in 100 said guide.

3. In a stop mechanism of the character described, tripping mechanism, a catch adapted to actuate said tripping mechanism, a shaft designed for interlocking engagement with the catch, means for moving the catch in a direction to operate the tripping mechanism upon the disengagement of the catch and shaft, a casing in which the catch is mounted, independently movable detectors 110 in contact with the yarn or yarns and direct connections between said shaft and said detectors to rotate the shaft on its axis to disengage the catch upon the occurrence of 115 a fault in the yarn. 120

4. In a stop mechanism of the character described, trip actuating mechanism, including a spring-actuated catch, a casing in which said catch is mounted, a shaft extending across said casing and journaled therein 125 having means thereon to engage the catch and provided at its ends with fingers, and detector fingers mounted on the respective ends of said shaft and independently movable into engagement with the first named 130

fingers, whereby to disengage the shaft from the catch.

5. In stop mechanism of the character described, the combination with tripping mechanism, including a spring actuated catch formed with a shoulder, a casing in which said catch is mounted, a shaft journaled in said casing and provided with a lug adapted to engage said shoulder, a crank 10 arm connected to said shaft, a link rod connected to said crank arm, a disk to which one end of the link rod is eccentrically connected, a support for said disk, a tension detector over which the yarn is adapted to be passed, a knot catcher for the yarn, the disk being formed with an apertured lip and a tensioned rod passing through said apertured lip and pivotally connected to the tensioning finger.
- 20 6. In mechanism of the character described, the combination with trip mechanism, including a catch, of means for holding said catch in a set position, and means tending to release said catch, said last named 25 means including a disk, a support for said disk, a link rod pivotally connected to said disk, two tension detectors over which the yarn or the like is adapted to be passed, knot catchers for the yarn, the disk being formed 30 with a laterally elongated lip formed with separate and distinct apertures, and tensioned link rods pivotally connected to the tension detectors, and passing rearwardly therefrom through the respective apertures 35 of the lip and formed in the rear of said apertures with hooks, whereby either rod may turn the disk without moving the other rod.

7. In mechanism of the character described, the combination with trip mechanism, including a spring actuated catch, of a casing in which said catch is mounted, the catch being formed with a shoulder, a shaft journaled in said casing and provided 40 with a lug adapted to engage said shoulder, means tending to move the shaft in a direction to effect the engagement of the lug with the shoulder, a tension detector finger over which the yarn or the like is adapted to be 45 passed, a knot catcher for the yarn, and means whereby the movement of said finger will automatically strip the yarn therefrom and disengage the lug of the shaft from the catch.

- 50 8. A knot catcher for use in a yarn actuated stop motion device comprising a rotatable member having an axial bore and a plurality of radial separated arms, each arm having a knot or stub detaining slot of selected width in a plane substantially at right angles to its axis of rotation.

- 55 9. In a knitting machine stop motion, a rotatively adjustable knot-catcher comprising radial slotted arms, a headed stud on which said device is mounted, a pin on the

head, the knot catcher having slots for engagement by the pin to hold the selected arm in position for use, and a spring to hold the pin and slot in engagement.

10. A machine of the character described, 70 including a casing, a support therefor, a stop device for the yarn, carried by said casing, a spring pressed catch mounted in the casing, a shaft journaled in the casing and provided with a lug adapted to engage said 75 catch to hold it in an inoperative position against the tension of its spring, an upper link rod connected to said shaft to turn the same, a horizontally disposed bracket, a disk journaled on said bracket and to which the 80 upper end of said link rod is eccentrically connected, a tension detector finger pivotally carried by the bracket at the forward end of the latter and over which the thread or yarn is adapted to be passed, a tensioned rod 85 pivotally connected to said tensioning finger and connected to the disk to turn the same upon downward and rearward pressure being imposed upon said finger, a link rod connected to and extending downwardly from the catch, a latch connected to the lower end of said last named link rod and provided with a shoulder, an arm for detachable engagement with said shoulder, a trip shaft to which the arm is connected, means 90 tending to move the trip shaft in an operative direction, and a belt shifting device adapted to be tripped by the said movement of the arm.

11. In mechanism of the character described, the combination of a catch, a setter shaft arranged to hold the catch in an inoperative position, means for actuating the catch upon its release from the setter shaft, 100 means for operating the setter shaft automatically, as specified, to release it from the catch, a link rod connected to said catch, a shouldered latch connected to said link rod, an arm adapted to engage said shoulder, a trip shaft spring pressed in one direction 105 and adapted to be held against movement with its spring under tension by the engagement of said arm with the latch, a brake lever, means for holding said brake lever in an inoperative position, means tending to 110 move the brake lever into operative position upon being released from said holding means, an automatic belt shifter, and means actuated by the movement of said trip shaft to disengage the brake arm from its holding means and for automatically tripping the belt shifter.

12. In a knitting machine stop-motion a plurality of yarn detectors, a power-release device, trip mechanism for the release device, comprising an upwardly extending tension member or link rod for releasing the trip mechanism, and mechanism for actuating the tension member upon the operation of any of the detectors comprising a casing, 120 125 130

- a transverse shaft in said casing, a spring 5 pressed pivoted catch to which the tension member is eccentrically connected, a lug on the shaft to restrain movement of the catch, 10 and a plurality of eccentric members on the shaft independently connected to the said detectors.
13. In a stop motion device for knitting machines power-release devices, a support, 15 a plurality of yarn tension detectors formed as levers with yarn-engaging ends, links engaging the other end of said levers and each engaging a common connection to said release devices, and independently adjustable tension springs mounted on said support and acting longitudinally upon said links.
14. In a knitting machine stop motion, detector mechanism actuated upon the occurrence of a fault in the material under manufacture, trip mechanism, and connec- 25 tions to the detector mechanism, a spring actuated throw-off, an operating shaft and handle therefor, a rock shaft having a crank to actuate said handle to throw off the power, a spring-pressed machine brake having an element pivoted to swing toward the power shaft, but having freedom of movement in another plane, a fixed shoulder in the machine frame normally supporting the brake element in an idle position, a second 30 crank arm on the rock-shaft to move and disengage the brake; and connections from the trip mechanism to operate the rock-shaft.
- In testimony whereof I hereunto affix my 35 signature in the presence of two witnesses.
